LEO J. GRUBMAN, OF BELLE HARBOR, NEW YORK

METHOD AND MEANS FOR MILLING EYE SOCKETS IN DOLL HEADS

Application filed March 1, 1927. Serial No. 171,769.

This invention relates to an improved method and means for milling eye sockets in doll heads, and has for its primary object to provide a method whereby the eye member receiving sockets may be accurately formed after the doll head has been completely closed with the exception of the neck opening and which substantially eliminates all possibility of human error and insures a symmetrical curvature of the eye socket walls with respect to the upper and lower edges of the individual eye openings as well as correspondence in the relationship between one socket and eye opening with the other. To this end, the new method consists essentially in operatively arranging a milling cutter through the neck of a doll head for bodily shifting movement to positions in cutting engagement with the doll head wall in accurately centered relation to the respective eye openings, and supporting the doll head for movement in a single direction as the cutting action progresses while positively preventing turning movement of said head in either a horizontal or a vertical plane with respect to the milling cutter.

It is another important object of the invention to provide a simply constructed means for operatively mounting or supporting the milling cutter whereby the cutter may be bodily moved about an imaginary fulcrum or point located in a plane intersecting its axis of rotation to position the cutter in definite operative relation to the spaced eye openings in the doll head wall.

It is another object of the invention to provide as an important part of the apparatus a means adapted to cooperate with means internally formed on the wall of the doll head which prevents any turning or bodily movement of the doll head with respect to the milling cutter but permits of its angular movement in one direction to maintain uniform pressure of the doll head wall at the upper and lower edges of the eye opening therein against the milling cutter as the cutting action progresses.

In a practical embodiment of the invention, I provide a rotatably mounted support for the milling cutter and an operating

motor therefor, the spindle of the milling cutter being positioned at an oblique inclination and intersecting the extended axial center line of the support so that upon the rotation of said support, the cutter may be moved about the imaginary fulcrum located at said point of intersection and positioned at either side of said center line.

It is a further general object of the invention to provide a machine or apparatus having the above noted characteristics which will be efficient in its operation, and in which the several parts are of simple construction and compactly mounted and arranged and in the operation of which special skill on the part of the mechanic is not required.

With the above and other objects in view, the invention consists in the improved method and means for milling eye sockets in doll heads, and in the several novel features of the disclosed apparatus, as will be herein-after more fully described, illustrated in the accompanying drawings, and subsequently incorporated in the subjoined claims.

In the drawings, wherein I have illustrated one simple and practical embodiment of the means or apparatus and in which similar reference characters designate corresponding parts throughout the several views,—

Figure 1 is a side elevation, the doll head being shown in section and mounted in position with respect to the milling cutter;

Fig. 2 is a top plan view of the machine;

Fig. 3 is a front elevation partly in section, and

Fig. 4 is a detail horizontal sectional view taken on the line 4—4 of Fig. 1.

Referring in detail to the drawings, the operative parts of the apparatus are mounted upon an obliquely inclined arm 6 integrally formed with a suitable base 5 which is adapted to be bolted, clamped or otherwise fixedly secured upon a work bench, table or other support.

In an opening 7 provided in the arm 6, a supporting means for the milling tool and its operating motor is rotatably mounted. This supporting means, as herein shown includes a disc 8 snugly fitting in the opening 7 and having an outwardly projecting an-

5   gular flange 9 extending upon a suitably formed seat 10 on the upper surface of the arm 6. A lower disc 11 is rotatably engaged with the under side of the arm 6 and is provided with a radially extending groove or key-way indicated at 12 to receive a locking rib or key 14 formed upon the plate 13 extending across the under side of the disc 11. The discs 8 and 11 are rigidly connected with 10 each other by the screw 15 which also is preferably threaded into a bore or socket in the end of the plate 13 as shown at 16 in Fig. 1 of the drawing. A second screw 17 is also engaged through registering openings in the 15 plate 13 and disc 11 and is threaded upwardly into the disc 8.

Upon one end of the plate 13, a downwardly extending obliquely inclined arm 18 is formed and upon the lower end of said arm 20 the operating motor 19 for the spindle 20 of the milling cutter 21 is suitably mounted. The spindle 20 extending through the elongated bearing extension 22 on the upper end of the motor casing has its axis positioned 25 in substantially parallel relation with the arm 18, and it will therefore, be understood that the said spindle is obliquely inclined with respect to the axis of rotation of the supporting discs 8 and 11. Each of these 30 discs is provided at one side of its center with an opening 23 and 24 respectively, and the plate 13 is provided with an aligned opening 25 to accommodate the extension 22 of the motor casing.

35   In order to overcome the tendency of the parts 8 and 11 to rotate on the arm 6 due to vibration in the operation of the motor 19 and to secure the necessary stability, I preferably provide upon the arm 18 and below 40 the plane of the plate 13, a suitably formed weight 26.

At the opposite side of the motor 19, the 45 end of the plate 13 is extended to form a suitable handle 27 by means of which the two discs 8 and 11 together with the operating motor may be rotated as a unit upon the arm 6. This rotation of the supporting means for the milling cutter is definitely limited in each direction by means of the 50 adjustable stop screws 28 which are threaded in the lugs 29 on the under side of the arm 6 at opposite sides of the rotatable support. The plate 13 is formed with an upstanding lug 30 which is adapted for contact with the 55 ends of these adjustable stop screws as seen in Fig. 2 of the drawings.

Upon the upper end of the inclined arm 6, the lower end of a bracket member 31 is rigidly fixed. This bracket member has an 60 intermediate angularly disposed portion 32 positioned in a plane substantially parallel with the plane of the arm 6 and having an opening 33 therein through which the milling cutter spindle 20 extends. To the upper 65 end of the bracket member 31 an arcuately

curved or crescent shaped plate 34 is fixedly secured at its center, the outer edge of said plate at the ends thereof being inwardly beveled or inclined as indicated at 35.

70   The doll head as shown at D is provided with the usual spaced eye openings *d* in its front wall and each side wall of the doll head is internally formed with a horizontally extending groove *d'*, the said grooves being located in accurate relation to the centers of the eye openings *d*. The base walls of these grooves are obliquely inclined in substantial conformity to the inclined edges 35 of the 75 plate 34.

76   In the use of the apparatus above described, the doll head is arranged over the milling cutter 21 and the upper end of the spindle 21 and the upper portion of the bracket 31, the said parts passing easily through the neck opening of the doll head. The doll head is manipulated until, by the 80 sense of touch and observing one end of the plate 34 through one of the eye openings *d*, the ends of said plate are positioned in the grooves *d'* on the opposite sides of the doll head wall. Upon moving the handle 27 in one direction to engage the lug 30 against one of the stop screws 28, the milling cutter 21 will be positioned with its geometrical center disposed in a plane which intersects the center of one of the eye openings *d* and with said cutter in contact with the inner surface of the front wall of the head at the edges of said eye opening. The motor 19 is 85 then set in operation so that the tool 21 will rapidly mill or cut out the material of the doll head wall at the inner side thereof, said cutter being of spherical form producing a concave socket in said wall. The operator 90 has only to maintain a light pressure upon the outer side of the front wall of the doll head to hold the same in contact with the tool 95 as the cutting action progresses. Owing to the fact that the ends of the plate 34 are snugly engaged in the grooves 35 on the side walls 100 of the doll head, there is no possibility of the head turning or rotating bodily in either a horizontal or a vertical plane about the axis of the cutter 21. Therefore, it is not possible 105 for the operator, even intentionally to produce a greater pressure of the head wall upon the cutting tool at one edge of the eye opening *d* than at the other edge thereof. Accordingly, the curvature of the wall of the 110 socket will be symmetrical with respect to the upper and lower edges of the eye opening. Therefore, when an oscillatory eye member 115 is subsequently mounted in the eye socket, the pupil thereon will move in accurate relation with respect to the edges of the eye opening in the opening and closing movements of the eye member and the free non-binding oscillatory motion of the eye member is also 120 assured. After one eye socket has thus been milled, the operator then moves the lever 125

130

handle 27 to rotate the cutting tool and its operating motor through a path of substantially 180° until the lug 30 abuts against the other stop screw 28. In this rotation of the tool support, it is obvious that since the axis of the tool 20 is positioned in an obliquely inclined plane, that the cutting member 21 will move about an imaginary fulcrum or point in the axial line of the spindle indicated at 20' in Fig. 3 of the drawings which intersects the extended axial center line of the rotatable support, thus positioning the spindle with its axis in a reverse obliquely inclined plane indicated by the broken line C in Fig. 3 of the drawings. By the proper adjustment of the stop screws 28, this turning movement of the spindle support is definitely limited in accordance with the known distance between the centers of the eye openings d in the doll head. Thus, without removing the doll head D from its supported position on the ends of the plate 34, the cutting tool 21, after having milled out one of the sockets may be quickly positioned in accurately centered relation to the other of the eye openings. The motor 19 is then again operated to mill out the socket at the inner side of the latter opening. The operator by observing the relation between a point on the cutting tool 21 and the edge of the eye opening at the outer surface of the head wall insures the cutting or milling of the two sockets to the same diameter. Thus, the relationship between the curved wall of the socket and one of the eye openings will accurately correspond with the relationship between the other eye opening and the wall of the socket associated therewith.

The apparatus above described may be employed for the milling of the eye sockets in doll heads of different sizes, it being only necessary to select the plate 34 of the proper width and to adjust the stop screws 28 so as to limit the bodily movement of the milling cutter in accordance with the spacing between the centers of the eye openings in the particular doll head. It will be apparent that my new method and apparatus for milling the eye member receiving sockets assures absolute uniformity in the product so that eye settings designed for application to heads of a certain size will be interchangeable with other doll heads of the same size. It will also be seen that I accomplish this desirable result by mechanical means which is of very simple construction and which insures the greatest accuracy without necessitating a high degree of skill on the part of the mechanic. In certain co-pending patent applications, I have disclosed different devices for milling the eye receiving sockets in doll heads, and in one of these prior embodiments, two separate spindles are provided to simultaneously operate upon the doll head wall while in another instance, I have disclosed a single milling cutter. In each of these cases however, it

is necessary to use a gauge or sighting means and reliance must be placed to a certain extent upon the skill of the workman in properly adjusting and positioning the doll head with respect to this sighting means. Therefore, in the present instance, by eliminating such gauge devices and reducing the possibility of a human error to a minimum, I secure greater uniformity in the product. Also, since the present apparatus may be operated with great rapidity, there is no appreciable reduction in the quantity production of the product.

In the accompanying drawings, I have illustrated an embodiment of the machine or apparatus, which has produced excellent results in practice. Nevertheless, in so far as my new method and the essential features of the disclosed apparatus are concerned, the same might be exemplified in numerous other alternative structural forms, and I accordingly reserve the privilege of resorting to all such legitimate changes therein as may be fairly embodied within the spirit and scope of the invention as claimed.

I claim:

1. The method of milling eye receiving sockets in doll heads which consists in positioning a milling cutter and its spindle through the neck of the doll head and operatively engaging the cutter with the head wall at the inner side of one of the eye openings therein and rotating the cutter to mill an eye receiving socket in said wall, and then oscillating the spindle in a gyratory path with respect to an imaginary fulcrum intersecting its axis and spaced from the cutter to operatively engage the cutter with the head wall at the other of the eye openings and rotating the cutter to form a second eye receiving socket.

2. The method of milling eye member receiving sockets in doll heads which consists in positioning a milling cutter and its spindle through the neck of the doll head and supporting the doll head against horizontal or vertical turning movement while permitting of an angular bodily movement of the head to engage the inner side of the head wall at the edges of one of the eye openings with the milling cutter, and then rotating said cutter to form the eye receiving socket with the wall thereof in symmetrical relation to the edges of the eye opening.

3. The method of milling eye member receiving sockets in doll heads which consists in positioning a milling cutter and its spindle through the neck of the doll head and supporting the doll head against horizontal or vertical turning movement while permitting of an angular bodily movement of the head to engage the inner side of the head wall at the edges of one of the eye openings with the milling cutter, then rotating said cutter to form the eye receiving socket with the wall

thereof in symmetrical relation to the edges of the eye opening, and then moving said milling cutter spindle and the doll head relative to each other to operatively position the cutter at the inner side of the other eye opening and milling a second eye receiving socket in the head wall.

4. The method of milling eye member receiving sockets in doll heads which consists in 10 positioning a milling cutter and its spindle through the neck of the doll head and supporting the doll head against horizontal or vertical turning movement while permitting of an angular bodily movement of the head 15 to engage the inner side of the head wall at the edges of one of the eye openings with the milling cutter, then rotating said cutter to form the eye receiving socket with the wall thereof in symmetrical relation to the edges 20 of the eye opening, and then oscillating the spindle in a gyratory path with respect to an imaginary fulcrum intersecting its axis and spaced from the cutter to operatively position the cutter in contact with the head wall 25 at the other of the eye openings therein for milling a second eye receiving socket in said wall.

5. In an apparatus for milling eye receiving sockets in doll heads, a spindle adapted 30 for insertion through the neck opening of a doll head and a milling cutter on one end of said spindle, and means for mounting said milling cutter spindle for movement in a gyratory path with respect to an imaginary fulcrum intersecting its axis in spaced relation 35 to the milling cutter whereby the cutter may be operatively positioned in contact with the wall of the doll head at the inner sides of the spaced eye openings thereof.

40 6. In an apparatus for milling eye receiving sockets in doll heads, a spindle adapted for insertion through the neck opening of a doll head and a milling cutter on one end of said spindle, means for mounting said milling cutter spindle for movement in a gyratory path with respect to an imaginary fulcrum intersecting its axis in spaced relation to the 45 milling cutter whereby the cutter may be operatively positioned in contact with the wall of the doll head at the inner sides of the spaced eye openings thereof, and a relatively fixed means for supporting the doll head against horizontal or turning movement relative to the milling cutter.

55 7. In an apparatus for milling eye receiving sockets in doll heads, a spindle and operating motor therefor, a milling cutter on one end of said spindle, said spindle and milling cutter adapted for insertion through the 60 neck opening of a doll head, and means for movably supporting said spindle and its operating motor for movement with respect to an imaginary fulcrum intersecting the axis of the spindle in spaced relation to the cutter whereby said cutter may be positioned in

operative engagement with the inner side of the doll head wall at either of the eye openings thereof.

8. In an apparatus for milling eye receiving sockets in doll heads, a rotatable support, 70 a spindle mounted on said support adapted for insertion through the neck opening of a doll head and having a milling cutter at one end, and said spindle being obliquely positioned with its axis in intersecting relation 75 to the axial center line of the support at a point between said support and the milling cutter, whereby upon the rotation of said support, the milling cutter may be moved within the doll head from an operative position in 80 opposed relation to one of the eye openings to an operative position in opposed relation to the other of the eye openings.

9. In an apparatus for milling eye receiving sockets in doll heads, a rotatable support, 85 a spindle mounted on said support adapted for insertion through the neck opening of a doll head and having a milling cutter at one end, and said spindle being obliquely positioned with its axis in intersecting relation to the axial center line of the support at a point 90 between said support and the milling cutter, whereby upon the rotation of said support, the milling cutter may be moved within the doll head from an operative position in opposed relation to one of the eye openings to an operative position in opposed relation to the other of the eye openings, and adjustable stop means for limiting the rotation of the support in each direction. 100

10. In an apparatus for milling eye receiving sockets in doll heads, a rotatable support, a spindle mounted on said support adapted for insertion through the neck opening of a doll head and having a milling cutter at one end, and said spindle being obliquely positioned with its axis in intersecting relation to the axial center line of the support at a point between said support and the milling cutter, whereby upon the rotation of said support, the milling cutter may be moved within the doll head from an operative position in 105 opposed relation to one of the eye openings to an operative position in opposed relation to the other of the eye openings, and an operating motor for said spindle carried by and movable with said support. 110

11. In an apparatus for milling eye receiving sockets in doll heads, a rotatable support, a spindle mounted on said support adapted for insertion through the neck opening of a doll head and having a milling cutter at one end, and said spindle being obliquely positioned with its axis in intersecting relation to the axial center line of the support at a point between said support and the milling cutter, whereby upon the rotation of said support, the milling cutter may be moved within the doll head from an operative position in 115 opposed relation to one of the eye openings to an operative position in opposed relation to the other of the eye openings. 120

12. In an apparatus for milling eye receiving sockets in doll heads, a rotatable support, a spindle mounted on said support adapted for insertion through the neck opening of a doll head and having a milling cutter at one end, and said spindle being obliquely positioned with its axis in intersecting relation to the axial center line of the support at a point between said support and the milling cutter, whereby upon the rotation of said support, the milling cutter may be moved within the doll head from an operative position in 125 opposed relation to one of the eye openings to an operative position in opposed relation to the other of the eye openings. 130

openings to an operative position in opposed relation to the other of the eye openings, an operating motor for said spindle carried by and movable with said support, a relatively fixed bracket member also adapted to extend through the neck opening of the doll head, and a member fixed to said bracket to engage internally formed parts on the wall of the doll head and support the doll head against 10 rocking movement relative to the milling cutter.

12. In an apparatus for milling eye receiving sockets in doll heads, a rotatable support, a spindle mounted on said support adapted for insertion through the neck opening of a doll head and having a milling cutter at one end, and said spindle being obliquely positioned with its axis in intersecting relation to the axial center line of the support at a point between said support and the milling cutter, whereby upon the rotation of said support, the milling cutter may be moved within the doll head from an operative position in opposed relation to one of the eye openings to an operative position in opposed relation to the other of the eye openings, an operating motor for said spindle carried by and movable with said support, a relatively fixed bracket member also adapted to extend through the neck opening of the doll head, a member fixed on said bracket and having spaced parts adapted for engagement with internally formed means on opposite sides of the doll head to support the doll head with its longer axis positioned in a definite obliquely inclined plane with respect to the axis of rotation of said support.

13. In an apparatus for milling eye receiving sockets in doll heads, a base, a support rotatably mounted on said base having an opening extending obliquely therethrough with respect to its axis of rotation, a motor mounted on said support, and a spindle operated by said motor extending through the opening in the support and having its axis intersecting the axial center line of its support at a point in spaced relation thereto, a milling cutter fixed on said spindle, said spindle adapted for insertion through the neck opening of a doll head, and means for rotating said support through an arc of substantially 180° to thereby move the inclined spindle about said point of intersection of its axis and the axial center of the support to move the milling cutter from an operative position in opposed relation to one of the eye openings in the doll head wall to an operative position in opposed relation to the other of the eye openings.

14. In an apparatus for milling eye receiving sockets in doll heads, a base, a support rotatably mounted on said base having an opening extending obliquely therethrough with respect to its axis of rotation, a motor mounted on said support, and a spindle op-

erated by said motor extending through the opening in the support and having its axis intersecting the axial center line of the support at a point in spaced relation thereto, a milling cutter fixed on said spindle, said spindle adapted for insertion through the neck opening of a doll head, means for rotating said support through an arc of substantially 180° to thereby move the inclined spindle about said point of intersection of its axis and the axial center of the support to move the milling cutter from an operative position in opposed relation to one of the eye openings in the doll head wall to an operative position in opposed relation to the other of the eye openings, a bracket fixed upon said base and also adapted to extend through the neck opening of the doll head, and means carried by said bracket to cooperate with parts of the doll head wall and support the doll head with its longer axis in a definite obliquely inclined plane with the relation to the axis of rotation of the support.

15. In an apparatus for milling eye receiving sockets in doll heads, a base, a support rotatably mounted on said base having an opening extending obliquely therethrough with respect to its axis of rotation, a motor mounted on said support, and a spindle operated by said motor extending through the opening in the support and having its axis intersecting the axial center line of the support at a point in spaced relation thereto, a milling cutter fixed on said spindle, said spindle adapted for insertion through the neck opening of a doll head, means for rotating said support through an arc of substantially 180° to thereby move the inclined spindle about said point of intersection of its axis and the axial center of the support to move the milling cutter from an operative position in opposed relation to one of the eye openings in the doll head wall to an operative position in opposed relation to the other of the eye openings, a bracket fixed upon said base and also adapted to extend through the neck opening of the doll head, and a plate secured on said bracket having end portions adapted to be received in internal grooves formed in the opposite side walls of the doll head to prevent turning movement of the doll head and support the same with its longer axis in a definite obliquely inclined plane with relation to the axis of rotation of the support.

In testimony that I claim the foregoing as my invention, I have signed my name hereto.

LEO J. GRUBMAN.
